UNITED STATES PATENT OFFICE.

ALONZO R. KIBBE, OF NEW RICHMOND, WISCONSIN.

WASH-BOARD.

SPECIFICATION forming part of Letters Patent No. 397,430, dated February 5, 1889.

Application filed January 7, 1887. Serial No. 223,687. (No model.)

To all whom it may concern:

Be it known that I, ALONZO R. KIBBE, a citizen of the United States, residing at New Richmond, in the county of St. Croix and State of Wisconsin, have invented certain new and useful Improvements in Wash-Boards, of which the following is a specification.

My invention relates to a wash-board constructed entirely of wood and provided with rollers over which the clothes to be washed may be rubbed, said rollers being provided with suitable journals to adapt them to be turned, as will be described.

The rollers are provided with projections or wings, preferably four in number, on each roller, forming thereby the desired and requisite surface or surfaces for rubbing purposes.

The uprights of my improved wash-board are provided with suitable bearings or sockets, in which the journals or spindles of the aforesaid rollers seat and turn, one of the said uprights being formed in such a manner that the rollers may be removed if one or more of them become broken, and new ones substituted in their place. This part of my invention also provides for a means of adjusting the tension on the rollers, whereby they can be tightened or loosened, and can be made to revolve easily or with difficulty, as may be desired.

Referring to the accompanying drawings, which form a part of this specification, Figure 1 represents a cross-section of one of the rollers of my improved wash-board. Fig. 2 is a vertical section of my wash-board. Fig. 3 is a front elevation of the same. Fig. 4 is a side view of upright 1, looking from the right-hand side of Fig. 3; and Fig. 5 is a section on line xx , Fig. 2, the rollers not being shown.

In the drawings, 1 represents the side or one of the uprights of my improved wash-board, and 2 the other upright or side. The rollers are represented at 3, and are provided with suitable spindles or journals, 4, as shown in Fig. 3. These rollers are set into the sockets of the upright 1, and into the corresponding sockets also of the upright 2.

The former upright is constructed in the following manner: As shown in Fig. 3, it is divided over a portion or all of its length into two parts. This divided or separated portion is co-extensive with aforesaid rollers

3, and is indicated in the drawings at 5. It may be hinged at 6 to the main portion of 55 the upright 1, with thumb-screws for tightening and adjusting the same; or it may simply be provided with the thumb-screws, as may be desired. In this case the hinges would be omitted, as they are not absolutely 60 essential.

The thumb-screws 7 may be of either metal or wood, and they extend through the portions 5 and 8 of the upright, thus binding them together and holding the rollers safely 65 and securely between them.

When one of the rollers 3 becomes broken or mutilated, the thumb-screws 7 may be turned out and the broken member removed and a new one replaced in its stead. The 70 thumb-screws 7, together with the parts 5, then may be set back and tightened into place. I use this arrangement also for increasing or decreasing the tension on the journals of the rollers, as the latter may become 75 worn in the course of time, and may slip too easily in their bearings, when it will become necessary to tighten them up, as aforesaid. These arrangements, together with the fact that I make my wash-board entirely of wood 80 and form my rollers in the way described and shown in Figs. 1 and 2, render my invention a very available one for practical and everyday use.

Having thus described my invention, what 85 I claim as new therein, and desire to secure by Letters Patent, is—

In combination with a wash-board provided with rollers, a movable portion, 5, coextensive with the rollers, whereby the removal 90 and replacement of the rollers is facilitated, hinges 6, connecting the portion 5 at the side to the wash-board so that it may be swung to one side of the wash-board, and thumb-screws 7, screwing into portion 5 and the wash-board, 95 and adapted to adjust the tension of the portion 5 on the rollers, and whereby the rollers may be permitted to rotate at different degrees of speed or be rigidly secured to the wash-board, substantially as shown and described.

ALONZO R. KIBBE.
